BY *J. Smith Jr.*
ATTORNEY

UNITED STATES PATENT OFFICE.

AVEDIS D. AVEDISYAN, OF BOSTON, MASSACHUSETTS.

NON-REFILLABLE BOTTLE.

SPECIFICATION forming part of Letters Patent No. 677,919, dated July 9, 1901.

Application filed March 5, 1901. Serial No. 49,851. (No model.)

To all whom it may concern:

Be it known that I, AVEDIS D. AVEDISYAN, a citizen of the United States, residing at Boston, in the county of Suffolk and State of Massachusetts, have invented certain new and useful Improvements in Non-Refillable Bottles; and I do hereby declare the following to be a full, clear, and exact description of the invention, such as will enable others skilled in the art to which it appertains to make and use the same.

My invention relates to certain improvements in "non-refillable bottles"—that is to say, bottles that are incapable of being filled after decantation without more trouble and expense than it is worth to do the work—but my invention particularly has reference to that style and structure of such bottles as is shown and described in Letters Patent No. 626,516, issued to me June 6, 1899. In this patented construction I employed a divided cylinder which in assembled condition was surrounded by a sleeve of cork and the seat for the valve-sections was perfectly flat and there was an opening in the top of the cylinder, through which the liquid was supposed to flow when the bottle was decanted, all of which details of construction have proved to be disadvantageous to the successful operation of the improvement.

The object of the present invention is to improve upon the structure shown and described in said patent and at the same time to observe simplicity of construction and to avoid using any deleterious substance, such as metal, which would affect the nature of the liquid contained in the bottle.

In the accompanying drawings, which form a part of this application, Figure 1 is a vertical sectional elevation of a bottle equipped with my improvement; Fig. 2, a similar view, but showing the bottle in inverted position; Fig. 3, a detail elevation of the cylinder; Fig. 4, a detail elevation of one of the valve-sections, and Fig. 5 a detail plan view of the valve-seat block.

Similar numbers of reference denote like parts in the several figures of the drawings.

1 is a bottle of any suitable and ordinary shape, and 2 is the valve-seat block, cemented or otherwise secured within the neck of the bottle at the lower end thereof. It is my in-

tention, however, in the instance of certain bottles to form this valve-seat integral with the bottle during blowing of the latter, and I therefore do not wish to be limited in this respect. This valve-seat has an opening 3 in its bottom, which communicates with the bottle, and from diametrically opposite points of this opening small lugs 4 project for the purpose presently to be explained.

5 is the valve-seat proper, which is formed within the upper portion of the block and is curved in cross-section.

6 represents the valve-sections, each of which is the complementary half of a cone, the bottoms of the sections being smooth and rounded, as shown at 7, so as to fit snugly against the seat 5, while projected laterally from the side of each valve-section immediately above said rounded portions are small lugs 8, which when the valve-sections are assembled are diametrically opposite each other for the purpose presently to be explained.

9 is an integral cylinder the diameter of whose upper portion is less than the diameter of the inside of the bottle-neck, while the diameter of the lower portion is such that it will fit snugly within said neck, and this cylinder rests upon said seat-block and is cemented at its lower portion firmly to the neck. 10 is an annular ledge formed in the lower part of this cylinder, said ledge, when the parts are assembled, being immediately above the lugs 8, so that when the bottle is inverted the lugs will rest upon said ledge. This cylinder is hollow, and when secured in position within the neck of the bottle it incloses the valve-sections, and within this cylinder at the upper end is a solid plug 11, capable of sliding freely within the cylinder and provided with a recessed portion 12 in its lower part, so that when the bottle is standing on its base said plug will drop down over the tops of the valve-sections, and thereby hold the latter in closed condition, as clearly shown at Fig. 1.

13 represents openings formed within the sides of the cylinder at its small diameter at any suitable distance below the top, through which openings the liquid flows from the bottle when the latter is decanted. When the bottle is standing on its base, the plug 11 will not only hold the valve-sections closed, but will also close these openings 13, and when

the bottle is decanted the plug will drop by gravity away from the valve-sections and said openings, so as not to oppose the free passage of the liquid from the bottle. Immediately above these openings are guard-ribs 14, formed on the outside of the cylinder and preferably extending up to the top thereof, as shown more particularly at Fig. 3, the object of these ribs being to prevent a wire or similar appliance from being readily inserted into the openings 13 for the purpose of tampering with the valve.

15 is a small ball contained within the valve-sections and prevented from dropping into the bottle by means of the lugs 4. When the bottle is inverted, this ball will drop toward the ends of the valve-sections, as shown at Fig. 2, so as to hold them open as against atmospheric pressure. When liquid is poured 20 from the bottle, more or less of a vacuum will of course be formed, and if this ball or some equivalent device were not provided the atmospheric pressure would close the valve-sections, and would thereby cause considerable annoyance.

30 The seating of the valve-sections snugly against a rounded seat makes a liquid-tight joint, and when the bottle is inverted the lugs 8 of the valve-sections will rest upon the ledge 10, so that these valve-sections are thus provided with rocking pivots, which will greatly facilitate the opening of the valve, and the sections of the latter are cut away at their bases at the points where they meet, as 35 shown at 16, so as to permit of the rocking movements of said sections.

40 All of the parts as above described and contained within the neck of the bottle are made wholly of glass, and therefore there is nothing connected with my improvement which can in the slightest degree injure the liquid contained within the bottle.

45 It is not necessary, of course, that the lugs 8 should extend to the top of the cylinder, since this construction is precautionary rather than essential, and therefore I do not wish to be limited in this respect.

50 I prefer to use the ball within the valve-sections and the plug within the upper portion of the cylinder, since these elements insure a far better operation of my improvement and at the same time operate very effectively in preventing successful tampering with the valve-sections in an attempt to refill the bottle; but if both of these elements 55 were omitted liquid within the bottle could be poured out after a fashion, because the air would gradually work itself within the bottle to supply the partial vacuum if the bottle 60 were allowed to stand on its base for a short time after decanting, and also it would be a very difficult matter to keep the valve-sections open by any manipulation of the bottle during the attempt at refilling. I therefore 65 do not wish to be limited to the use of the plug and ball, although, as I said before, I should include them in my preferred construction.

Having thus described my invention, what I claim as new, and desire to secure by Letters Patent, is—

70 1. A bottle having a valve-seat block secured within the lower portion of its neck and provided with a valve-seat, a conical valve divided centrally and vertically and resting on said seat each half of said valve provided with exterior lugs at diametrically opposite points, the integral cylinder resting on said block and having an annular ledge immediately beyond said lugs, said cylinder being closed at its top and provided with lateral 75 openings in its upper portion, guard-lugs projecting externally from said cylinder immediately above said openings, and the recessed plug within said cylinder and capable of moving freely, substantially as set forth.

80 2. In a bottle, the combination of the neck having the valve-seat block open at its bottom and secured within the lower portion of said neck and provided with a rounded seat and having lugs projecting laterally from the 90 walls of the opening in the bottom, the conical valve-sections rounded at their lower extremities and fitting within said seat, and provided with diametrically opposite lugs immediately above the seat portions proper, the 95 ball inclosed by said sections, the integral cylinder secured within the neck of the bottle and inclosing the valve-sections and provided with a ledge immediately beyond the valve-lugs, said cylinder also having lateral 100 openings in its upper portion, and the recessed plug within the upper end of said cylinder and capable of moving freely therein, substantially as set forth.

105 3. A bottle having a valve-seat block and an integral cylinder secured within its neck, said cylinder being closed at the top and having openings in its sides and provided with a ledge immediately above said block, a sectional conical valve resting on said seat-block 110 and capable of a rocking movement and provided with exterior diametrically opposite lugs, and the recessed plug within the upper portion of said cylinder and capable of a free movement therein, substantially as set forth. 115

120 4. In a bottle, the combination of the open valve-seat block and the integral cylinder secured within the neck of the bottle, said cylinder being closed at the top and having lateral guarded openings near the upper end and 125 provided with a ledge at the lower end, the sectional conical valve resting by gravity on said seat-block and provided with exterior lugs which are diametrically opposite and which extend immediately below said ledge, 125 and the ball inclosed by said valve-sections, substantially as set forth.

130 5. In a bottle, the valve-seat block and the integral cylinder secured within the neck of the bottle, said block having an opening in its bottom and provided with a rounded seat, while the cylinder is closed at the top and has lateral openings near its upper end and is provided with a ledge at the lower end, and

the sectional conical valve resting on said seat and provided with exterior lugs immediately below said ledge, substantially as set forth.

- 5 6. In a bottle, the combination of the seat-block secured within the neck of the bottle and having an opening in its bottom and provided with an annular rounded seat, the integral cylinder closed at the top and having 10 its lower end secured within the neck of the bottle immediately above said block, the bottom of said cylinder having an interior ledge while the upper portion has a diameter less than the inside diameter of the bottle-neck

and is provided with lateral openings, and 15 the vertically-divided conical valve inclosed by said cylinder and having its lower portion seated snugly within said seat and provided with exterior lugs which extend immediately below said ledge from the middle portion of 20 each valve-section, substantially as set forth.

In testimony whereof I affix my signature in presence of two witnesses.

AVEDIS D. AVEDISYAN.
